UNITED STATES PATENT OFFICE.

LUCIAN F. FORSEILLE, OF CINCINNATI, OHIO.

FLUID CONDENSING OR HEATING DEVICE.

1,410,561.

Specification of Letters Patent. Patented Mar. 28, 1922.

Application filed May 27, 1920. Serial No. 384,694.

To all whom it may concern:

Be it known that I, LUCIAN F. FORSEILLE, a citizen of the United States of America, and resident of Cincinnati, in the county of 5 Hamilton and State of Ohio, have invented a new and useful Improvement in a Fluid Condensing or Heating Device, of which the following is a specification.

An object of my invention is to provide a 10 device that will have a maximum radiating surface without obstructing the flow of the fluid.

Another object of my invention is to provide a device for the purpose stated, that can 15 be easily cleaned.

These and other objects are attained by the means described herein and disclosed in the accompanying drawing in which:

Fig. 1 is a transverse sectional view on 20 line 1—1 of Fig. 2.

Fig. 2 is a transverse sectional view on line 2—2 of Fig. 1.

My invention comprises a casing A having the water box a formed at its head and the 25 water box a' formed at its base. A series of tubes a^2 , triangular in cross section, extend vertically between the water boxes. The substance to be cooled, oil for example, passes around the tubes as it passes from the oil 30 inlet b to the oil outlet b' of the cooling chamber B formed within the casing.

The casing A has a base water box a' into which cold water is fed through the water inlet a^3 . The tube sheet a^4 forms the upper wall 35 of the box a' . The tubes a^2 extend through the tube sheet a^4 and are attached thereto, extending upward and passing through the upper tube sheet a^5 that forms the bottom of the upper box a . The space between 40 the tube sheets a^4 and a^5 comprises an oil chamber B. The tube sheet a^5 is secured between the sections a^6 and a^7 of the casing by means of the flange a^8 formed on the tube sheet. Gaskets a^9 are utilized to provide a 45 fluid proof connection between the casing parts and the tube sheet a^5 . The lower tube sheet a^4 has a ring or flange a^{10} of rubber or fibre formed about it, that seats in the V shaped groove formed at the junction of the 50 casing sections a^7 and a^{11} . This connection is fluid proof and permits the expansion of the parts when they are heated. The tubes a^2 are triangular in cross section and are ar-

ranged in such way that there will be no direct passage in the path that must be followed by the oil as it moves through the device. To accomplish this, the adjacent sides of adjoining tubes are placed parallel to one another, the parallel sides being at an angle to the direct line of passage that would be followed by the oil if the tubes were not there.

The baffle plates b^2 divide the chamber B into a continuous circuitous passage from the oil inlet b to the oil outlet b' . The oil in 65 passing through the device is obliged to pass from side to side of the device because of the openings b^3 placed at alternate ends of the adjacent baffle plates. A series of tube sections a^{12} space the baffle plates, the rods b^4 70 extending through the tube sections and through the baffle plates and holding the baffle plates and the tube sheets in a constant relation to one another.

The operation of my device is as follows: 75

The hot oil enters the chamber B through the port b and follows the path indicated by the single headed arrows, by referring to Fig. 2 it will be readily apparent that the oil will repeatedly come in contact with the 80 radiating surface of the same tubes. As the oil moves from side to side through the device, it must follow a circuitous path between the tubes because there are no right angles formed upon any of the tubes and 85 because there are no direct passages from the opening b^3 in any one baffle plate to the opening b^3 in the baffle plate next below. The water or cooling agent enters the port a^8 and follows the path indicated by the 90 double headed arrows leaving by way of port a^{13} . The passage of the water through the device is quicker and its path so much shorter than the passage and path of the oil that a very rapid cooling of the oil is 95 possible. The water boxes a and a' may be dispensed with and air will pass through the tubes a^2 , serving as the cooling medium.

What I claim is:

1. In a device of the class described the 100 combination with a casing of a chamber within the casing and having an inlet and an outlet port, of a series of baffles within the chamber, and a series of tubes angular in cross section extending through the cas- 105 ing and the baffle plates and forming a series

of circuitous passages between the baffle plates and at angles to a direct line of passage of a fluid between the baffle plates.

2. In a device of the class described the combination with a casing, of a chamber within the casing, baffle plates in the chamber, a series of tubes passing through the baffle plates and the casing and being tri-

angular in cross section, the adjacent sides of adjoining tubes being parallel, said parallel sides being at an angle to a direct line of passage of a substance between the baffle plates.

In witness whereof, I have hereunto subscribed my name this 25th day of May, 1920. 15

LUCIAN F. FORSEILLE.
